BRAKING DEVICE FOR FEEDING MEANS OF
PILGERING MILLS

Josef Gassen, Dusseldorf-Oberkassel, Germany,

Dusseldorf, Germany, a corporation of Ger-
many

Application July 31, 1934, Serial No. 737,726
In Great Britain August 3, 1933

3 Claims. (Cl. 80—14)

My invention relates to braking devices for feeding means of pilgering mills.

In the rolling of tubes on pilgering mills, a tube blank carried on a mandrel is fed rapidly forward to the pilgering rolls after each revolution of the rolls. In order to protect the parts of the mill against heavy shocks and breakage, braking devices are usually associated with said feeding means.

A braking device suitable for that purpose is for instance disclosed in Patent 1,833,990 to Hans Dreyer in which a liquid is compressed on each forward stroke of the feeding means which liquid in its turn compresses a mass of air enclosed in a vessel. The compression of the enclosed air results in braking the feeding means and the parts moving together with it.

Now, for obtaining a high output from a mill in a given time, it is necessary to have a high feeding speed of the blank. The higher the speed, the more powerful, on the other hand, the braking force required for stopping the rapidly moving masses. With the old arrangements, an increase of the braking force was only possible in a manner which considerably reduced the speed of the feeding means all over the forward travel so that nothing was gained on the whole by the increased speed.

It is an object of my invention to provide a braking device for feeding means of pilgering mills of the type disclosed in the aforementioned patent by which powerful braking can be obtained without the speed of the feeding stroke being materially impaired.

A further drawback of known braking devices is that, in the course of their operation, the air is highly heated by its continual compression. Since the pressure of the air is also influenced by its temperature, it is obvious, that the braking effect exerted on the feeding means will vary with the number of strokes. A uniform braking effect is, however, very desirable.

It is, therefore, a further object of my invention to provide means by which a uniform braking effect will be secured.

In the drawing, I have shown a preferred embodiment of my invention, the only figure being a longitudinal section through the feeding means of a pilgering mill which is equipped with my novel braking device.

1 are the rolls of a pilgering mill of known shape which work on a tube blank 2 carried by a mandrel 3. The latter is rigidly connected by a coupling box 13 to feeding means which comprise a rod 4 and a piston 5 adapted to recipro-

cate in a cylinder 6. The latter is filled with a fluid under pressure which drives the piston 5 and the parts connected thereto forward towards the pilgering rolls 1 when the latter are not working the blank 2 and pushing it back against the pressure of the fluid.

Cylinder 6 is supported by a bed plate 9 which also carries a second cylinder 7 forming a part of the braking device. Rod 4 extends through the cylinder 7 and has a shoulder 14 which acts as a plunger on a suitable liquid 15 contained in cylinder 7 when the rod 4 is reciprocated. An abutment ring 8 for the plunger 14 is provided at the outer end of cylinder 7. Attached to cylinder 7, and projecting above it, is an air vessel 16 in free communication with the cylinder 7.

According to the present invention, vessel 16 is of cylindrical shape formed with an upwardly tapered portion. As the plunger 14 advances on its forward stroke when the tube blank 2 is fed to the pilgering rolls 1, the liquid 15 is forced more and more into the vessel 16 thereby compressing the air enclosed in that vessel which brings about a braking effect on plunger 14 and the feeding means. Because of the preferred form of the vessel 16, that compression is much more intense at the end of the feeding stroke than at its beginning so that all the required braking effect can be obtained during the last part of the feeding stroke, while the speed of the feeding means during the first part is left substantially unimpaired.

In order to adjust the braking effect to different conditions, a shut-off valve 12 is provided at the upper end of vessel 16 for the liquid 15 to be introduced or withdrawn.

Furthermore, the vessel 16 is provided with a cooling means by which the heat developed in the air is absorbed so that its temperature will be maintained even throughout the whole time of operation. To this end, I surround vessel 16 with a jacket 10 filled with a cooling medium 11 which may be water, oil, gas or simply air. The medium is admitted and discharged at different levels by pipes shown in the drawing.

I claim:

1. In a braking device for the feeding means of pilgering mills, the combination with a cylinder filled with a liquid and a braking plunger adapted to reciprocate in said cylinder and operatively connected with the feeding means, of a closed air-filled vessel in direct communication with said cylinder having a constricted upper portion so disposed as to offer a rapidly increasing powerful resistance to the liquid displaced

by said plunger toward the end of the feeding stroke.

2. The combination as specified in claim 1, including a cooling jacket surrounding the constricted upper portion of said vessel.

3. In a braking device for the feeding means of pilgering mills, the combination with a cylinder filled with a liquid and a braking plunger mounted for reciprocation in said cylinder and

operatively connected with said feeding means, of a closed air-filled vessel in direct communication with said cylinder, being of substantially cylindrical shape and terminating in a bottle-neck upper portion offering a rapidly increasing powerful resistance to the liquid displaced by said plunger toward the end of the feeding stroke. 5

JOSEF GASSEN.
